UNITED STATES PATENT OFFICE.

CHARLES H. HAIG, OF NEW YORK, N. Y.

CLEANING DEVICE FOR TOBACCO-PIPES AND THE LIKE.

1,081,038.

Specification of Letters Patent.

Patented Dec. 9, 1913.

Application filed December 7, 1911. Serial No. 664,475.

To all whom it may concern:

Be it known that I, CHARLES H. HAIG, a citizen of the United States of America, and a resident of New York, in the county of 5 New York and State of New York, have invented a certain new and useful Cleaning Device for Tobacco-Pipes and the like, of which the following is a specification, the same being a full, clear, and exact description 10 of the invention, such as will enable others skilled in the art to which it appertains to make and use the same.

This invention relates to devices adapted for use primarily in cleaning the orifice or 15 bore of tobacco pipes, although the same may be employed, if desired, to remove the oily secretion or sediment, or collected matter from the interior of cigar holders, etc., and it has for its object the provision of 20 an apparatus of the kind set forth, simple in construction, inexpensive to manufacture and which is also efficient in practical use.

To attain the desired end, the invention 25 consists in the construction, arrangement and operation of parts herein set forth.

In order to enable my invention to be 30 fully understood, I shall proceed to explain the same by reference to the drawings, 35 illustrative of embodiments of the invention, which accompany and form a part of this specification, and in which—

Figure 1 is a perspective view of an appliance constructed according to my invention, Fig. 2 is a central longitudinal section 40 of a pipe into which my cleaning device is shown as having been partially inserted, and Fig. 3 is a perspective view of another device in which the invention is embodied.

Like letters of reference indicate like 45 parts in all the views.

Referring particularly by reference characters or symbols to the drawings, A denotes a slender bar which preferably consists of a flat or round wire or other suitable material, which slender bar is preferably flexible and made of such material as to have an inherent resilience or camber to give it sufficient body to perform the operation 50 for which it is designed, the said slender bar being preferably long enough to extend through the stem or stick of the pipe into the pipe bowl.

The pipe bowl and stem terminal are preferably separable, although my device may be advantageously employed in cleaning

5 pipes of other construction, and my invention is adapted to be used both in cases where the pipe stem is straight and where it is curved, and also both in pipes where the entire bore of the same is straight or in alinement, and where different portions thereof are angularly arranged as regards each other, so as to constitute a passage or channel of an approximately V-shape. A 10 bend is preferably made in the slender bar near the free end thereof, as at a, in order that the same may be adapted, as it were, to feel its way into an angularly disposed portion of the bore where such may 15 occur, the flexibility of the wire being such that the said bend does not interfere in any manner with the slender bar being passed through a straight stem pipe. I ordinarily provide the free end a of the slender bar A 20 with an enlarged or blunt point which may be formed in any suitable manner, and the same may consist of any suitable or desired means, as for example, preferably an open loop, as a², or a solid head, as a³. The other extremity of the slender bar A is preferably 25 constructed and arranged to be attached to an absorbent flexible fabric or material by any suitable or desired means, as, for example, preferably by means of an eyelet a⁴ 30 or by being wound around the said absorbent material, as at a⁵. The absorbent flexible fabric or material I prefer to use 35 ordinarily consists of a strand of cotton or other suitable textile substance ordinarily 40 having a series of alternately raised and depressed portions as, for example, the porous material B preferably twisted, plaited, or braided in such a manner as to have a preferably uniform twist or spiral ridge or helix 45 b, the pitch of the same being ordinarily 50 the same throughout the length of the strand, although if desired the flexible textile material may consist of a strand B', 55 illustrated in Fig. 3, having at suitable intervals or distances along its length portions larger in diameter than the remaining parts, as at b'.

My pipe cleaning device may be coiled in 60 small compass, and when uncoiled will still 65 retain sufficient stiffness or rigidity for efficient use, or it may be held in a more straightened relation, or else with the curvature as shown, when placed on sale, as in either event it will, when free, resume its 70 normal shape owing to the temper of the slender bar.

By introducing the free end of the flexible and preferably resilient slender bar into the stem of the pipe, etc., it will work its way up through the same and into and through the pipe bowl, and upon drawing the absorbent flexible textile material back and forth through the stem, all nicotin and collected matter will be absorbed and removed, and the smoke passage will be thoroughly cleaned, and the subsequent smoke will consequently be rendered less acrid, and therefore more pleasant and enjoyable.

I wish it to be understood that I do not desire to be limited to the exact details of construction shown and described, for obvious modifications will occur to a person skilled in the art.

What I claim as my invention is:—

As a new article of manufacture, a cleaning device of the class described comprising a resilient wire having guiding means

near the outer end of the same and terminating forward of the guiding means in an enlarged blunt entering-point, the said wire extending backwardly from said guiding means and shaped to approximately conform to the bore of a pipe, and having a securing means located at the inner end of the wire, in combination with a fibrous material detachably engaged with the said securing means and being of greater thickness than the wire, whereby the cleaning device may be introduced and pulled through the pipe in one direction.

In testimony of the foregoing specification I do hereby sign the same in the city of New York, county and State of New York this second day of December, 1911.

CHARLES H. HAIG.
